FRANK D. LEWIS, OF WEST ORANGE, NEW JERSEY, ASSIGNOR TO PATHÉ FRERES PHONOGRAPH COMPANY, OF NEW YORK, N. Y., A CORPORATION OF DELAWARE.

AUTOMATIC STOP MECHANISM FOR PHONOGRAHS.

1,394,776.

Specification of Letters Patent. Patented Oct. 25, 1921.

Application filed December 30, 1919. Serial No. 348,380.

To all whom it may concern:

Be it known that I, FRANK D. LEWIS, a citizen of the United States, and a resident of West Orange, county of Essex, and State 5 of New Jersey, have invented certain new and useful Improvements in Automatic Stop Mechanism for Phonographs, of which the following is a specification.

My invention relates to automatic stops 10 for phonographs.

By the present invention the reproducing means in its movement over the record serves at a predetermined point in its movement to release a movable member, which upon being 15 released moves under any suitable actuating force or influence as, for example, the force of gravity, and interposes within the path of movement of a motor actuated element, as, for example, a downwardly extending 20 projection of the turntable, means whereby a brake or stop is operated to stop the motor. In this way the motor itself supplies the power for releasing the stopping device, and there is practically no drag upon or interference with the free movement of the sound 25 reproducing means.

The present invention is further directed to the application of such an automatic stop to a phonograph of the tympanum type, in 30 which a diaphragm of large dimension is used without a horn.

In the accompanying drawings Figure 1 is a perspective view of automatic stop mechanism embodying my invention as applied 35 to a tympanum phonograph.

Fig. 2 is a side view partly in section.

Fig. 3 is a fragmentary detail view showing how the automatic stop may be used with a phonograph of the ordinary tone arm 40 type.

Fig. 4 is a detail view of a shoe and supporting finger.

Figs. 5 and 6 are plan views showing the turntable brake in retracted and released 45 positions respectively.

Fig. 7 is a fragmentary view showing the parts in position for lifting the gravity member, and Fig. 8 is a section on line 8—8, Fig. 7.

Reference character 10 is applied to the 50 tympanum or sound producing means, mounted in a frame 11. Frame 11 is provided with a tubular arm 12, swiveled for vertical movement on yoke 13. Through the 55 tympanum tube 12 passes a link 14, by

means of which vibrations are imparted from a stylus or tracking member 15, adapted to track the grooves of sound record 16 on turntable 17, to the tympanum 10. Shaft 18 of yoke 13 is in turn mounted for rotation 60 in the bracket 19 secured to the phonograph cabinet 20. The sound reproducing means thus has universal angular movement.

Means are provided for controlling the stop mechanism. Said means is adapted to 65 normally turn with shaft 18, but is shiftable with respect thereto. In the form shown, shaft 18 has a tapered or conical thrust member 21 fixed thereto by screws 22, and shaft 18 and the sound reproducing apparatus carried thereby is supported by said thrust member 21 within a hollow conical or tapered seat 23 in a finger 24, which in turn rests on bearing members, as the flat washers 25, 26. With this arrangement, 70 when shaft 18 is rotated finger 24 turns with it, but if finger 24 should be held while shaft 18 is turned by tube 12, the position of the finger will be shifted or changed with respect to shaft 18 and tube 12. 75

Finger 24 serves to control a lightly movable member which may be actuated in any convenient way. In the form shown gravity is relied on for its actuation and for this reason the movable member is termed herein 80 the gravity arm. Said gravity arm is designated by reference character 27, and, like all the parts of the apparatus, is preferably made of a thin sheet metal stamping. It has downwardly bent ears on each side and a 85 horizontal pivot pin 28 is passed through such ears and through similar ears struck up from the material of the sheet metal base 29, adapted to be screwed to the instrument board 30, and serving as a convenient base- 90 plate, on which the various parts of the stop mechanism are mounted, so that the complete mechanism can be readily assembled 95 together on the base plate, in advance of applying same to the phonograph. 95

Thus the apparatus can be readily included in original manufacture, or be subsequently applied to completed or used machines.

Gravity member 27 has a preferably part 105 circular shoe 31, which overweights this end of the gravity member slightly, so that it will fall if not supported. Shoe 31 is normally supported during sound reproduction by finger 24, but the overweight of this end 110

of the gravity arm is so slight that the finger 24 moves freely along under shoe 31 with practically no friction.

Shoe 31 has a notch 32 on its under side 5 which is adapted to be entered or engaged by finger 24, so that when finger 24 comes under notch 32 the shoe end 27' of the gravity member 27 falls, the finger entering the notch.

10 The opposite end 27" of gravity member 27, which rises at such times, carries a lever 33, having an inclined surface 34 adapted to be interposed, by upward movement of arm 27" of member 27 on which it is borne, 15 within the path of a pin 35 extending downwardly from turntable 17, which is, of course, actuated from the phonograph motor. When arm 27" of member 27 is down, by reason of shoe 31 riding on finger 24, the 20 lever 33 is withdrawn from the path of pin 35. A stop 33' is provided on arm 27 to limit the movement of lever 33 inwardly or toward the path of pin 35.

The turntable brake or stop lever 36 is 25 pivoted at 37 on the base plate 29. It has an arm 38 extending outwardly beyond the turntable, by which it may be manually operated, a second arm 39 which may be used to lift end 27' of gravity arm 27 and thereby to disengage finger 24 from notch 32, and 30 a third arm 40, which is provided with the brake shoe 41, adapted to bear against the interior of the flange on turntable 17. Spring 36' tends to turn member 36 and to 35 bring the brakeshoe into braking or stopping position.

The arm 40 of member 36 is also provided with a downwardly extending catch 42, adapted to be engaged with the shoulder 43 40 of a notch 44 in a lever 45, so that the parts are held in the position shown in Fig. 5. Lever 45 is pivoted to base plate 29 at 46. Its outer arm 45' extends out beyond the turntable for manual manipulation of the 45 lever. Its inner arm 45" is provided with an upwardly extending lug 47 adjacent to lever 33, of sufficient height to be contacted by and actuated from lever 33 in all positions of gravity arm 27. Arm 45' of lever 45 and arm 39 of stop lever 36 are spring held 50 toward one another by the interposed contraction spring 36'.

The inner end 49 of notch 44 in lever 45 is extended beyond shoulder 43 for a sufficient 55 distance to permit stop lever 36 to be turned to the position shown in Fig. 7. In this position the end 50 of arm 39 engages the inclined under edge 51 of a lug 52 formed on an extension 53 of arm 27' of gravity arm 27, to lift this end of the gravity arm, if depressed, permitting the finger 24 to be disengaged from notch 32 in shoe 31.

60 The arm 27' of gravity arm 27 is formed with an inclined portion 54, and an angle lever 55 is provided pivoted fairly snugly to

the base plate 29 at 56, the inner arm 55' whereof is provided with the upstanding cam shaped lug 57 adapted to engage the inclined surface 54 of gravity member 27 to lift arm 27' thereof in order to support shoe 31 above 70 finger 24, keeping lever 33 below pin 35 and rendering the automatic stop apparatus temporarily inoperative when not desired for use. The arm 55" of lever 55 projects outwardly beyond the turntable, so as to be conveniently located for manual manipulation. A screw 58 may be screwed into the instrument board through the slot 59 in gravity arm 27, and its head serves as a stop to prevent unduly great upward movement of the 80 end 27' of gravity arm 27.

In Fig. 3 a finger 24' frictionally supported upon a tone arm is shown in order to indicate one way in which the stop mechanism described herein may be applied to 85 phonographs of the tone-arm and horn type, and it may be applied to still other forms of sound reproducing instruments.

To operate the apparatus (assuming that the finger 24 is in notch 32, and end 27' of 90 gravity arm 27 is down) the tympanum tube 12 is turned so as to bring tracking member 15 to the desired stopping point, which may be and usually is at the close of a record, but may be at any place upon the 95 sound record. During this movement of the tympanum tube 12 and shaft 18, finger 24 remains stationary, being held in notch 32 of shoe 31 on gravity arm 22, and the tapered thrust member 21 turns in the seat 23 in 100 finger 24. This relative turning or shifting movement of these parts serves to set the apparatus for the desired stopping place for the particular record. Lever 36 is now turned until stopped by the back of catch 105 42 engaging the bottom of notch extension 49 in which position end 27' of gravity arm 27 is raised by arm 39 of lever 36 engaging the inclined surface 51 on lug 53 of the gravity arm, (see Figs. 7 and 8) and finger 110 24 is disengaged from notch 32. The movement of lever 36 has also disengaged shoe 41 from the brake shoe flange to start the motor and it remains disengaged, lever 36 stopping when released with catch 42 held by 115 shoulder 43 in the position of Fig. 5. The tympanum tube 12 is turned to the proper position upon the record for the commencement of sound reproduction and the stylus or needle is lowered thereon to playing 120 position.

As sound reproduction takes place, shoe 31 rides freely and lightly upon finger 24 which turns under it. When the stopping position is reached, for which the stop mechanism was initially set, finger 24 is under notch 32, and the end 27' of gravity member 27 falls, the finger entering the notch; the end 27' of member 27 rises under the influence of gravity acting on the slightly overweighted end 130

27', lever 33 is interposed in the path of pin 35, which in passing engages the inclined surface 34 of lever 33 and turns lever 33, which engages lug 47, thereby turning lever 45, freeing catch 42 from shoulder 43 and releasing the brake, and stopping the motor, the parts assuming the position shown in Fig. 6.

If it be desired to stop the machine before the completion of sound reproduction, the 10 arm 45' of lever 45 is moved away from arm 38 of lever 36, whereupon the catch 42 is freed from shoulder 43 and the machine is stopped. If it be desired to use the phonograph for a time without the automatic stop 15 feature, the lever 55 is operated to raise and hold the member 27 to such position that the shoe 31 is supported above and does not 20 coact with finger 24, and to restore the same, lever 55 is moved in the opposite direction. When the automatic stop feature is dispensed with, handles 38 and 45' are used 25 respectively for starting and stopping the phonograph in the usual manner. The lever 55 may also be used to raise end 27' of gravity arm 27 and thereby disengage finger 24 from notch 32 at any time when it is not 30 desirable to make use of lever 36 for this purpose because of its other functions.

30 The construction shown is for the purpose of affording an understanding of my invention and not for limitation. Changes and modifications may be resorted to within the scope of my claims without departing from 35 or sacrificing the advantages of my invention.

I claim:

1. In automatic stop mechanism for phonographs, stop control means having a taper 40 seat, and sound reproducing means supported by said control means and having a taper bearing in said seat.

2. In automatic stop mechanism for phonographs, a stop control finger having a 45 taper seat therein, sound reproducing means, a shaft therefor, and a taper bearing for said shaft received and supported in said taper seat.

3. In automatic stop mechanism for phonographs, stop control means, sound reproducing means, and a connection therebetween comprising a tapered member received 50 in a tapered seat.

4. In automatic stop mechanism for phonographs, a rotatable stop control member, 55 sound reproducing means of the tympanum type and comprising a shaft, and a friction

bearing for said shaft in said control member.

5. In automatic stop mechanism for phonographs, sound reproducing means including a tympanum, a tympanum frame and tube, a yoke in which said tube is mounted, a substantially vertical yoke shaft, a tapered bearing on said shaft, a stop control finger 60 65 having an opening for said shaft, and a tapered seat for receiving said tapered collar.

6. In automatic stop mechanism for phonographs, a movable member, control means 70 therefor actuated by travel of the sound reproducing means across a record, a brake lever and retaining means therefor, a motor actuated element, means for releasing said brake lever from its retaining means 75 interposable by movement of said movable member into the path of said motor actuated element, and an extension on said brake lever for operating said movable member.

7. In automatic stop mechanism for phonographs, a pivoted gravity arm, a brake lever, means for holding it retracted, means controlled by the gravity arm for releasing the brake lever, and an extension on the 80 85 brake lever for turning the gravity arm on its pivot.

8. In automatic stop mechanism for phonographs, a brake for stopping the motor, an operating handle therefor, means for setting the brake to stop the motor including a 90 gravity arm, and means directly connected to move with said handle for lifting the gravity arm.

9. In automatic stop mechanism for phonographs, a brake lever, brake operating 95 means comprising a gravity arm and a control member therefor, adapted to be engaged thereby, and means on said brake lever for disengaging the control member from the gravity arm.

10. In automatic stop mechanism for phonographs, sound reproducing means, stop control means movable therewith, a gravity arm normally adapted to coact with said stop control means and having a cam like 105 surface, and a lever having means to engage said inclined surface and to lift said gravity arm and support it above said control means, whereby the automatic operation of the stop mechanism is dispensed with when desired. 110

In testimony that I claim the foregoing, I hereto set my hand, this 23rd day of December, 1919.

FRANK D. LEWIS.
